INVENTOR,
Samuel C. Allen,
BY Howard S. Smith,
His ATTORNEY

UNITED STATES PATENT OFFICE

SAMUEL C. ALLEN, OF NEAR DAYTON, OHIO, ASSIGNOR TO THE DAYTON STEEL RAC-
QUET COMPANY, OF DAYTON, OHIO, A CORPORATION OF OHIO

METAL ARROW AND METHOD OF MAKING THE SAME

Application filed May 3, 1928. Serial No. 274,806.

This invention relates to new and useful improvements in metal arrows and the method of making the same.

It is one of the principal objects of my invention to provide a metal arrow which is light, strong, straight, elastic and resilient, and whose flight is steady, unwavering, and smooth. The tubular metal shaft is grooved for fletching, the nocks are correct and the tips will split wood without being bent or loosened.

Another object of the invention is to provide a method of making these arrows from steel tubing, which is efficient, and labor-saving.

For the purpose of applying the feathers to the grooved end of the steel shaft, I provide a fletching fixture which makes this step of the method as expeditious and accurate as the others.

Other important and incidental objects will be brought out in the following specification and particularly set forth in the subjoined claims.

In the accompanying drawing illustrating my improved metal arrow and its method of manufacture, Figure 1 is a perspective view of one end of the tubular steel shaft before it is grooved. Figure 2 is a perspective view of the same after it is grooved for fletching. Figure 3 is a cross-sectional view taken through the grooved end of the shaft on the line 3—3 of Figure 2. Figure 4 is a longitudinal sectional view taken through the rear end of the tubular shaft, showing how the nock is applied to it. Figure 5 is an end view thereof. Figure 6 is a longitudinal view taken through the front end of the tubular shaft, showing how the pile is soldered into it. Figure 7 is an end view of the pile. Figure 8 is a perspective view of the fletching fixture, showing how the feathers are applied to the grooved end of the steel shaft within it. Figure 9 is a cross-sectional view showing how the vein of a feather is held in a groove by the pins of the fixture during the gluing operation. And Figure 10 is a perspective view of the rear end of the steel shaft after the nocks and feathers have been applied to it.

The metal arrow illustrated in these drawings is made in the following manner. First, a plain tube 1 that is preferably constructed of alloyed steel is cut off to the desired length and weighed. The tube should not be too light to hold up under extreme conditions of use, and in the present instance should not be under five-eighths of an ounce.

One end of the tube is then formed with three axial grooves 2 to receive the veins of the feathers that are applied in a fletching fixture to be hereinafter described.

The tube which is grooved as shown in Figures 2 and 3, is then cut to the exact length desired, which in the present instance is $27\frac{3}{16}$ inches.

The tube is then heat-treated and polished, after which it is straightened by passing it between rollers or other means to remove the kinks.

The inside surface of the end of the tube 1 opposite its grooved end is then polished to receive the reduced cylindrical part 3 of a hardened steel pile 4, which is soldered in place within the tube (see Figures 6 and 7). This end of the tube is then polished.

The tubular shaft 1 is then re-straightened to take out any kinks which were not removed in the first straightening operation.

The shaft is then nickel plated, after which it is ready for the application of the feathers by sandblasting the grooves 2 to remove the dirt from them.

The fletching operation is performed with the assistance of a fixture such as the one which will now be described. Referring to Figures 8 and 9, the numeral 5 designates a side member to which two end blocks 6, 6 are secured to provide an arrow receiving frame. The end blocks 6, 6 are formed in their top edges with grooves 7, 7 to receive the steel shaft 1 to support it during the application of the feathers to its grooved end.

A feather 8, is applied as follows: The tube 1 is placed in the fixture with a groove 2 facing upward as shown in Figures 8 and 9. Glue or other suitable adhesive is then applied to the rib of the feather, which is then set in the groove. This is then held in

the groove by the following means until the glue dries.

Referring to Figures 8 and 9, the numeral 9 designates a flat holding piece which is hingedly secured to the top of the member 5 adjacent the rear end block 6. Projecting inwardly from the inner edge of the holding piece 9 are pins 10, preferably three in number, which are adapted to pass through a feather just above its rib to press the latter firmly in the top groove 2 of the tube. Sufficient tension for this purpose is applied to the holding piece by a helical spring 11 secured between it and the side member 5.

After the rib of the feather 8 becomes fixedly set in the upper groove 2 of the tube, the holding piece 5 is raised against the tension of the spring 11 to withdraw the pressure pins from the feather so that the tube may be turned to bring another groove 2 into position to receive a feather 8. The time consumed in applying a feather to the tubular shaft 1 in the fletching fixture is from 15 to 20 minutes.

After all the feathers have been applied to the grooved end of the tube 1, they are cut to the style desired. The tube is then removed from the fletching frame and its grooved end cleaned and rust proofed on the inside. This end of the tube is then nickel-plated.

The next operation is the insertion of a nock 12 in the grooved end of the tubular shaft. This nock, that is preferably made of aluminum, has a reduced inner end 13 which has a tight fit in the end of the tube. The wall of the tube is then indented into the end 13 of the nock or formed with depressions which enter depressions in the nock, as shown in Figures 4 and 5, to firmly secure it within the tube.

The rear end of the tubular shaft 1 is then polished and painted.

The finished arrow is then flight tested, preferably by the flight-testing device illustrated and described in my application for Patent Serial No. 271,318 filed April 19, 1928.

A steel arrow constructed under the method or process just described is strong, light, and elastic, and has a flight which is steady, unwavering and smooth.

Having described my invention, I claim:

1. An arrow comprising a metal tube, a metal pile secured to the anterior end of the tube, a metal nock insertable in the posterior end of said tube, and depressions struck from the wall of the tube for entrance in depressions formed in the nock to firmly secure the latter in the tube.

2. The herein described method of making a metal arrow, which consists in forming external axial grooves in one end of a steel tube, then inserting a metal pile in the other end of said tube, then securing feathers in

said grooves, and then inserting a nock in the grooved end of the tube.

3. The herein described method of making a metal arrow, which consists in forming external grooves in one end of a steel tube, then heat-treating, polishing and straightening said tube, then soldering a metal pile in the anterior end of the tube, then securing feathers in said grooves, and then securing a metal nock in the grooved end of the tube.

In testimony whereof I have hereunto set my hand this 27th day of April, 1928.

SAMUEL C. ALLEN.
